UNITED STATES PATENT OFFICE

2,539,662

MEGAPHONE FOR WIND INSTRUMENTS

Leonard L. Gilcrease, Hanford, Calif.

Application January 14, 1949, Serial No. 70,925

4 Claims. (Cl. 84—453)

1

The present invention relates to improvements in a megaphone for a wind instrument, and it particularly relates to an apparatus which will increase the sound of wind instruments of narrow shape. Such instruments have little tone volume due to the lack of a large instrumental body. Typical of such instruments are the flute and clarinet.

Many instruments are provided with a body which will increase the sound volume. Such instruments are, among others, the trumpet, the trombone, and the saxophone.

The present invention deals with tubular-shaped, narrow instruments. Their sound will be drowned out in an orchestra when competing with the type of instrument that contains a volume building body unless reinforced by several artists playing the same passage. This invention puts the narrow, tubular-shaped instruments on a more equal basis, and improves their sound quality and resonance at the same time. It is well known to persons skilled in the art, that in some sound producing horns the pitch of the notes is determined by the vibration of the lips. In these instruments the horn merely prevents the sound waves from dispersing, and rather sends them uniformly in the direction of its outlet opening. This creates in the distance the effect of an increase in sound volume. This is utilized in any megaphone, be it a radio speaker or an automobile horn.

This principle is used in my invention. I am using a wind instrument which produces the pitch of the notes by means of tone-holes and not by vibration of the lips. At the same time I provide a megaphone surrounding the instrument which will direct the tone volume in a certain direction before the tones escape into the open.

It is an object of my invention to overcome the tonal defects originating in the ordinary wind instrument of the clarinet type.

It is another object to produce a medium which will increase the sound of instruments which have practically no volume building body of their own, by confining the sound waves produced by the instrument and sending them in one direction.

It is a further important object of my invention to combine an improvement which will produce the desired pitch by the advantageous use of tone holes; with an instrument body adapted to create the impression of a larger sound volume by directing all of the emanating sound waves in a certain direction.

It is another object of this invention to provide means for gaining access to the tone holes of a

2

wind instrument surrounded by a casing, without appreciable loss of tone volume through the openings of the casing permitting access to the instrument for playing it.

Finally, it is an important object to provide access to the encased instrument in such a manner that the musician playing it is assured the full freedom in the movement of his fingers and hands over the instrument.

10 Other objects and advantages will appear in the following specification, and the novel features of the device will be particularly pointed out in the appended claims.

15 My invention is illustrated in the accompanying drawings forming a part of this application, in which:

Figure 1 shows a side view of the megaphone with an instrument mounted therein;

20 Figure 2 shows a front view of the megaphone; Figure 3 is a sectional view taken along the line III—III in Figure 1 and shows the instrument holding means;

25 Figure 4 is a sectional view taken along the line IV—IV in Figure 1 and shows the means for receiving the right hand of the player;

Figure 5 is another sectional view along line V—V of Figure 1 and shows the means for receiving the left hand of the player;

30 Figure 6 is a sectional view taken along the line VI—VI in Figure 5, and shows a further detail of the hand-receiving opening in the megaphone; and

35 Figure 7 is a longitudinal sectional view of the megaphone portion that houses the instrument and is taken along the line VII—VII in Figure 2.

While I have shown only the preferred form of my invention, it should be understood that various changes or modifications may be made within the scope of the appended claims without departing from the spirit and scope of the invention.

The wind instrument indicated generally at A, rests in a horn-shaped casing B. To hold the instrument A firmly in place, spring clips 1 and 1a clamp the body of the instrument to saddles 2 and 2a, respectively. The clips 1 and 1a are preferably located, one at each end of the instrument, and are secured to the saddles 2 and 2a. The saddles are mounted within the casing B. Since the instrument A is located approximately in the center of the casing B, the saddles will preferably form a half disc, as shown in Figure 3. In the drawings, a clarinet is shown located in the casing B, but any other wind instrument of somewhat similar shape may be used instead.

The instrument A is operated by means of opening or closing different combinations of tone holes 3, which can be closed by the fingers of the player, or else levers 4 may be employed for the same purpose. Air is blown into the instrument through the mouthpiece 5, which, as shown in Figure 1, protrudes from the entrance end of the casing B. Two clips 6 around the mouthpiece 5 serve to hold the reed to the mouthpiece.

It may become necessary to remove the instrument A from the casing B. For this purpose a cover C is made a part of the casing. Hinges 7 permit the opening and closing of the cover C. The latter and the hinges 7 are shown in Figure 2. A fastener 8 will hold the cover 6, while closed, safely to the casing. Reference is made to Figure 4. The casing B has a curved and conical body widening toward a bell end D.

While the instrument is being played, the casing B is supported by a strap E which is placed over the shoulder of the musician. Two eyelets 9 are used to secure the strap E to the megaphone.

In order to afford access to the sets of tone holes 3 and levers 4 which are operated by the musician's hands, large apertures F and G are provided in the casing opposite the respective sets of tone holes 3 and levers 4.

Usually, in a clarinet, the left hand operates the set of tone holes and levers disposed closer to the mouthpiece. Thus, the aperture F, nearer to the mouthpiece 5, is located on the left hand side of the casing B; the aperture G is located on the right hand side and opposite the lower sets of tone holes 3 and levers 4. This arrangement is shown in Figures 1 and 2.

The apertures F and G are closed by shields H and J, respectively. It is sufficient to describe the function of the shield H covering the aperture F, and it should be remembered that a similar arrangement applies to the aperture G.

The shield H is arcuate in shape and has two arcuate members 11 and 12. The numeral 11 represents the inner member and the numeral 12 the outer member. As shown in Figure 5, a hand-receiving sleeve 13 is secured to the members 11 and 12. The sleeve carries a flange 14, which is secured to the members 11 and 12 by rivets or other suitable fastening means. As indicated before, a similar arrangement applies to the lower aperture G, shown in Figure 4. There the respective parts carry the same numerals and letters, but have in addition the suffix a.

Thus the shields H and J are free to move peripherally and longitudinally along the casing B, and the sleeves 13 and 13a are free to be moved any place within the confines of the apertures F and G as indicated by the arrows X in Figures 4, 5 and 6. The purpose of the shield and sleeve arrangement is to furnish an entry just large enough to receive the musician's hand. If the sleeves were not movable, the musician would not be able to move his hands and fingers to different keys of the instrument. But the arrangement described forms hand-receiving passages freely movable which will cause the shields to slide and rotate freely according to the movements of the musician's hands. Full mobility of his fingers is preserved by the tapered appear-

ance of the sleeves 13 and 13a, and for all practical purposes no sound waves will escape from the casing B through the apertures F and G after the musician's hands have entered the sleeves.

5 I claim:

1. A megaphone for an instrument, comprising a horn-shaped casing adapted to surround the instrument; the instrument having its mouthpiece protruding from one end of the casing and having tone holes; and the casing having hand-receiving apertures affording access for the musician's fingers to the tone holes, and a hinged cover forming a part of the casing, said cover when opened permitting the insertion of or the removal of the instrument from the casing.

2. A megaphone for a wind instrument having sets of tone holes with levers for closing certain of the holes, comprising a casing adapted to surround the wind instrument; the casing having

10 large apertures; an arcuate shield covering each aperture; each shield being slidably supported by the casing and having hand-receiving openings moveable within the confines of each aperture affording access of the musician's hands to 25 operate manually the tone holes and levers, without any appreciable escape of sound waves through the hand-receiving opening.

3. In a megaphone for an instrument, a casing adapted to surround the instrument; the casing having hand-receiving apertures permitting the

30 playing of the instrument; an arcuate shield covering each aperture; each shield being movably supported by the casing and having two circumferentially movable members, one on the 35 inside and the other on the outside of the casing; both members being connected together; each shield having a hand-receiving opening movable within the confines of each aperture and affording access for the hands of the player of the 40 instrument.

4. In a megaphone for a wind instrument having sets of tone holes, a casing adapted to surround the wind instrument; the instrument having

45 its mouthpiece protruding from one end of the casing; the casing having an aperture disposed opposite each set of tone holes; an arcuate shield covering each aperture; each shield being supported by the casing and being slidably circumferentially and longitudinally of the casing, and each shield having a hand-receiving sleeve 50 movable within the confines of the casing and affording access of the musician's hands to each set of tone holes.
